UNITED STATES PATENT OFFICE

HARRY G. GRANER, OF BURLINGTON, IOWA

PLIERS

Application filed May 21, 1931. Serial No. 539,041.

This invention relates to pliers and has for the primary object, the provision of means whereby the jaws are capable of adjustment into varying working positions and capable of a greater number of adjustments than is possible to obtain with the conventional type of pliers, thereby permitting the gripping of objects having a much larger variance as to sizes than heretofore possible when employing the conventional type of pliers for such work.

With this and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a plan view illustrating pliers constructed in accordance with my invention and showing the jaws adjusted into a working position of the smallest degree.

Figure 2 is a similar view showing the jaws adjusted into a second working position.

Figure 3 is a plan view illustrating the pliers adjusted in a second working position with the jaws separated to their fullest extent.

Figure 4 is a similar view illustrating the jaws adjusted into a third working position and positioned in a fully separated position.

Figure 5 is an edge view illustrating the pliers.

Figure 6 is a plan view illustrating one of the elements of the pliers and constituting a body portion having a handle and an integral jaw.

Figure 7 is a similar view illustrating the other element of the pliers and including a body having a handle and an integral jaw.

Figure 8 is a sectional view taken on the line 8—8 of Figure 1.

Figure 9 is a perspective view illustrating a locking element.

Referring in detail to the drawings, the numeral 1 indicates pliers including handles 2 and 3 formed integral with body portions 4 and 5, respectively. Jaws 6 and 7 are formed integral with the body portions 4 and 5 as shown in Figure 1. The body portions 4 and 5 are pivotally connected by a headed bolt 8 extending through said bodies and having oppositely disposed flattened faces 9 and a nut 10 threaded thereon whereby the jaws 6 and 7 may be moved relative to each other by the movement of the handles 2 and 3. The body portion 5 is provided with an elongated slot 11, the walls of which are arcuately curved at spaced intervals to provide bolt receiving chambers 12, 13 and 14 having communication with each other by restricted portions. The restricted portions are of such a size that the bolt 8 may move from one chamber to another when said bolt is positioned with the flattened faces 9 parallel with the restricted portions between said chambers, however, when the bolt 8 is positioned with the flattened faces 9 disposed at an angle to the restricted wall between said chambers, the bolt will be prevented from moving from one chamber to another.

The body portion 4 is provided with an elongated slot 15 having chambers 16 and 17 formed in each end of the slot and being in communication with each other by said slot which forms a restricted passage between the chambers 16 and 17 so that the bolt 8 will be retained in either of the chambers 16 and 17 when the flattened faces are disposed angularly with the passage between said chambers. However, when the bolt is positioned with the flattened faces 9 parallel with the walls of the restricted passage, said bolt may be moved from one chamber to the other. It is to be understood that when the bolt is positioned to pivotally connect the body por-

tions 4 and 5 it extends through the slots 11 and 15.

A locking plate 18 is mounted on the bolt 8 between the head thereof and the body portion 4 and is provided with a tongue 19 adapted to engage into either of the notches or recesses 20 and 21. The locking plate 18 is provided with an elongated opening 22 to receive the bolt and the flattened faces 9 thereof for securing the locking plate against rotation relative to the bolt. A finger piece 23 is formed on the locking plate 18 whereby the latter may be moved to engage either the notch 20 or the notch 21.

With the body portions 4 and 5 positioned as shown in Figure 1, the jaws 6 and 7 are set at a zero working position and by positioning the handle 3 at right angles to the handle 2, the bolt 8 may be slid from the chamber 12 to the chamber 13 providing a second working position for the jaws as shown in Figure 2. By positioning the handles 2 and 3 again in the foregoing stated position, the bolt 8 may be moved from the chamber 13 to the chamber 14 giving a third working position for the jaws as shown in Figure 3. With the bolt occupying the chamber 14 and moving the locking plate or the tongue 19 thereof out of the notch 21 into the notch 20, the bolt 8 may then be moved from the chamber 16 of the body portion 4 into the chamber 17 thereby providing a fourth working position for the jaws.

When it is desired to return the jaws to their zero working position as shown in Figure 1, the operation heretofore described is repeated in a reverse manner. Therefore, it will be seen that an adjustment between the jaws has been provided which is capable of permitting the jaws to grip objects of varying sizes and to a range of sizes considerably greater than can be gripped by the conventional type of pliers in which one body portion is provided with a slot similar to the slot 15 while the other portion is provided with an opening to permit the bolt or pivot to extend therethrough.

While I have shown and described the preferred embodiment of my invention, it will be understood that minor changes in construction, combination and arrangement of parts may be made without departing from the spirit and scope of my invention, as claimed.

Having thus described my invention, what I claim is:

Pliers comprising body portions, handles on said body portions, jaws on said body portions, said body portions having slots provided with spaced restricted portions and enlarged portions forming chambers with communicating passages, a pivot bolt having oppositely disposed flattened faces extending through the slots and capable of being moved from one chamber of each body portion to

another chamber for adjusting the body portions relative to each other whereby the jaws may be adjusted to various working positions, one of said body portions having spaced notches, and a locking plate secured to the bolt and engageable with either of said notches and when in one position adapted to hold the bolt against adjustment relative to one of the body portions and when in a second position adapted to permit the bolt to be adjusted relative to said last named body portion.

In testimony whereof I affix my signature.
HARRY G. GRANER.
